(57) **CLAIM**

We claim the ornamental design for a telephone handset, as shown and described.

DESCRIPTION

FIG. 1 is a perspective view of a telephone handset showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown represent unclaimed subject matter only and form no part of the claimed design.

The dot-dash lines in the drawings define the bounds of the claimed design only and form no part of the claimed design.
